Int. Cl. D8—06

U.S. Cl. D8—136

FIG. 1

FIG. 2

FIG. 1 is a front perspective view of an electrical card key showing my new design; and

FIG. 2 is a side elevational view thereof.

The front and the rear of the card key are the same in appearance.

This application is a division of my earlier application entitled Combined Electrical Key and Case, Ser. No. D. 20,484, filed Dec. 12, 1969, now Pat. No. 220,557, granted Apr. 20, 1971.

I claim:

The ornamental design for an electrical card key, substantially as shown and described.
